(57) **CLAIM**

I claim the ornamental design for contoured support for human body, as shown.

DESCRIPTION

FIG. 1 is a perspective view of a contoured support for human body in accordance with the subject invention; FIG. 2 is a top plan view of the contoured support for human body of FIG. 1;

FIG. 3 is a bottom plan view of the contoured support for human body of FIG. 1;

FIG. 4 is a side view of the contoured support for human body of FIG. 1;

FIG. 5 is an opposite side view of the contoured support for human body of FIG. 1;

FIG. 6 is a rear view of the contoured support for human body of FIG. 1; and,

FIG. 7 is a front view of the contoured support for human body of FIG. 1.
